UNITED STATES PATENT OFFICE

2,394,824

APPARATUS FOR FEEDING METAL STRIP TO
METAL WORKING PRESSESRussell T. Todd, Youngstown, Ohio, assignor to
McKay Machine Company, Youngstown, Ohio,
a corporation of Ohio

Application June 7, 1941, Serial No. 397,060

17 Claims. (Cl. 153—54)

This invention relates to an improved apparatus for handling, processing, and feeding metal strip to a metal working press and also to an improved method and apparatus for controlling the operation of the handling and processing equipment and for controlling the movement of the strip relative to the cutting or working dies of the press. More specifically, the invention relates to an improved method and apparatus for handling, processing, and feeding metal strip to a continuously operating press whereby the strip may be automatically handled, processed, and fed in synchronism with the operation of the press in an entirely automatic manner thereby substantially increasing the productive capacity of the assembly while reducing stock waste to an absolute minimum.

The primary object of the invention is the provision of an improved method and apparatus for the purposes indicated above which is operative to supply the strip to the metal working press in a more accurate and dependable manner and in substantially improved condition whereby the productive efficiency of the press is increased and the product thereof is of a better and more uniform quality.

A further and more specific object of the invention is the provision of improved apparatus for carrying out the method of the invention which apparatus is rugged and durable in service and so arranged that a minimum of factory floor space is required for its installation and operation. The invention also contemplates the incorporation of such apparatus into compact self-contained units to be employed individually with each press. Thus, the individual unit may be set up for a particular press operation and when this is accomplished, the unit will automatically process and supply strip at high speed direct from the coils in which form the strip is normally supplied to the stamping or fabricating plant.

Another object of the invention is the provision of an improved uncoiler for uncoiling metal strip and of an improved arrangement for driving and controlling the operation of the uncoiler. Also, the invention seeks to provide an improved assembly for cleaning, processing continuous metal strip and to provide an improved interlocking control system for the various elements of the line including the uncoiling mechanism and the press.

Yet another object of the invention is the provision of an improved assembly for uncoiling, processing, and feeding continuous metal strip to a metal working press which is amenable to such control that the threading through of the stock and the setting up of the assembled mechanism including the adjustment of the measuring device are substantially simplified and facilitated where-

by the "off" time of the press line due to changing coils is materially shortened. Those and other objects and advantages of the invention will become apparent from a consideration of the following detailed specification and the accompanying drawings wherein there is disclosed a preferred embodiment of the invention.

In the drawings:

Figure 1, parts *a* and *b*, is a side view of an apparatus constructed in accordance with the principles of the invention;

Figure 2, parts *a* and *b*, is a plan view of the apparatus of Figure 1;

Figure 3 is an enlarged view of the strip scrubbing assembly of the apparatus of Figures 1 and 2;

Figure 4 is a fragmentary view of the apparatus of Figure 3;

Figure 5 is a fragmentary view of the metal strip process or utilized in the apparatus of Figures 1 and 2;

Figure 6 is a schematic representation of the strip measuring device of the apparatus;

Figures 7 and 8 are piping diagrams for the hydraulic drives for the uncoiling assembly and for the balance of the apparatus, respectively; and

Figure 9 is a wiring diagram of the control circuit for the apparatus of Figures 1 and 2.

The apparatus of the invention, in its preferred and illustrated embodiment, consists principally of a strip uncoiling assembly illustrated by Figures 1*a* and 2*a* and of a combination machine illustrated in Figures 1*b* and 2*b*, which machine consists in turn of a strip scrubbing or cleaning assembly, a cold working device or processor, a roller leveller, and a strip measuring device. Said machine is most advantageously constructed as a unitary compact assembly for purposes of economy in construction and operation, and would facilitate the control of the component parts of the machine. Interposed between the uncoiler and said machine is a short loop pit adapted to receive a length of the strip to insure the availability of the supply of strip for said machine regardless of the existence of some control lag in the operation of the uncoiler.

The strip uncoiling apparatus of Figures 1*a* and 2*a* comprises a base 10 on which is mounted spaced upstanding frames 11 and 12 in each of which is slidably mounted a guide carrier 13. Carriers 13 are positioned along a common axis and a coil side guide 14 is rotatably mounted on the inner end of each of the carriers. Each carrier is provided with a rack 15 which is adapted to be engaged by a pinion housed within the casing 16 and adapted to be driven by one or the other of the motors *m*₁ or *m*₂. This arrangement is provided to enable the rotating

side guides 14 to be moved toward and away from each other to accommodate coils of strips of varied widths for the purpose of preventing damage to the side edges of the coil or strip as explained in U. S. Patent No. 2,122,674 to Wardle.

Also supported on the base 10 but below and to either side of the axis of the guides 14 are bearing blocks 17 arranged in two groups of three each for the purpose of supporting the two spaced parallel coil carrying shafts 18. The outer of the blocks 17 are conveniently positioned in windows 19 formed from the lower portions of the frames 11 and 12, while the other of the blocks are positioned intermediate the ends of the shafts. A plurality of removable bands or sleeves 20 are mounted on each of the shafts 18 and these bands or sleeves are covered with brake lining material to provide sufficient driving friction between the shafts and the coil, while avoiding marring or scratching of the surface of the strip of the coil. Shafts 18 are arranged to be driven by a shaft 21 through suitable worm gearing, not shown, and shaft 21 is in turn arranged to be driven by a variable hydraulic motor $hm3$. Motor $hm3$ receives hydraulic fluid pressure from pump $hp3$ which in turn is driven by an electric motor $m3$.

Extending upwardly and outwardly from the rear edge of each of the frames 11 and 12 is a housing 22 in which is journaled a fixed guide roll 23, a pair of pinch rolls 24, a plurality of side guide rolls 25 to engage the side edges of the strip, and upper and lower guide rolls 26 to guide the strip as it leaves the uncoiler. The side guide rolls 25 are arranged to be moved inwardly and outwardly to accommodate strip of varied width by suitable and conventional mechanism, not shown, operated by a hand wheel 27. Also, the pressure exerted by pinch rolls 24 is adapted to be varied by manipulation of hand wheel 28 through well-known and conventional linkage, not shown. Pinch rolls 24 deliver the strip from the uncoiler and for this purpose are driven from shaft 21 through gearing housed in casing 29, shaft 30, and suitable gearing housed in casing 31. The pinch rolls 24 also perform the function of breaking down the scale on the strip. A fixed guide roll 32 positioned above and outwardly of the first guide roll 23 completes the assembly of parts carried by the housings 22. It should be observed that the pass plane through the rolls carried by the housings 22 is generally tangent to the natural curve taken by the strip 33 as the latter leaves the coil and extends in a downward direction for delivering the strip into a loop pit to be hereinafter described. It should be apparent that since the coil of strip is rotated by engagement of the sleeves 20 with the outer periphery of the coil, the linear speed of the strip as it leaves the coil may be correlated with the pass speed between the pinch rolls 24 and, consequently, the loop between the pinch rolls and the coil will be substantially constant regardless of the diameter of the coil.

The loop pit, above mentioned, consists principally of a downwardly curved frame-work 34 on which is journaled, by means of anti-friction bearings, a great number of fibre discs 35 which are adapted to support the strips at many spaced points. A limit switch $LS1$ is provided with an operating arm to be engaged by the strip when the latter fills the pit.

Referring now to Figures 1b, 2b and 3 through 6, the principal apparatus of the invention consists of a base 40 on which is mounted a pair

of spaced parallel housings 41 and 42 for the purpose of supporting the devices now to be described. Supported immediately in the housings 41 and 42 is a processing leveller which consists of a roller leveller indicated generally by reference numeral 53 and a metal working roll 43 positioned ahead of the roller leveller and adapted to be moved up through the plane of the pass of the strip through the machine, as indicated in Figure 5, to subject the strip to severe reverse bends for the purpose of cold working the strip thereby relieving inherent stresses therein, as is well understood in the art. Roll 43 is guided in vertical guides 44 secured to or forming part of the housings 41 and 42 and is backed up by offset rolls 45 journaled in a slide 46 arranged to be moved vertically by a toggle 47 operated by an arm 48 which is driven by a crank. The crank is arranged to be rotated by a motor RM through suitable speed reducing gearing 49. A pair of pinch rolls 50 is positioned in front of the processing roll 43 and a double pair of backed-up pinch rolls 51 are positioned between the processing roll 43 and the rolls of the leveller 53. The pinch rolls 51 are arranged to be adjusted to vary the pressure between them by manipulation of the hand wheel 54 which is coupled by means of worm gearing with conventional hold down screws 55. Likewise, pinch rolls 50 are adapted to be adjusted by manipulation of hand wheel 56 which is coupled to hold down screws 57 by means of shaft 58.

Positioned to one side of the processing leveller proper is a gear case 60 which is adapted to drive the rolls of the processing leveller, the levelling rolls being driven through flexible couplings 61, the pair of pinch rolls in front of the processing roll 43 by the flexible coupling spindles 62, and the pinch rolls between the processing roll 43 and the roller leveller by the flexible spindles 63. Incorporated in the drive for pinch rolls 50 is an overrunning clutch, not shown, which allows rolls 50 to rotate at a much higher rate of speed when the roll 43 is being elevated thereby drawing the strip into its looped path and through the pass between the rolls 50 and this overrunning clutch would, of course, normally prevent the driving of the rolls in the reverse direction. This free wheeling device is adapted to be bridged by a magnetically operated clutch indicated schematically at MC1, the operation of which will appear later.

Gear assembly 60 is driven by a hydraulic motor $hm6$ which is supplied with oil under pressure by the variable delivery pump $hp6$ driven by electric motor $m6$. The operation and features of this drive will be explained in connection with the hydraulic piping diagram and the electrical control circuit.

Supported on the front ends of the housings 41 and 42 are the sub-housings 65 and 66 arranged to support a scrubbing unit, shown more in detail in Figure 3 of the drawings. This scrubbing unit consists of lower brushing rolls 67 journaled in the housings 65 and 66 and upper opposite scrubbing rolls 68 adjustably journaled in blocks 69 slidably mounted for vertical movement in windows 70 provided in the housings. In accordance with usual practice, the brush rolls 67 and 68 are provided with kerosene sprays, not shown, to aid in removing scale from the strip and immediately after each of the pairs of brush rolls is a pair of rubber squeegees 71 to engage the top and bottom surfaces of the strip 75 to wipe the strip clean of scale, kerosene and

other foreign matter. The top rolls and squeegees, being carried by the blocks 69, are adapted to be raised and lowered as a unit to facilitate threading through of the strip by mechanism engaging the blocks. This may consist of bolts 72 having connection with the blocks 69 and extending up through bores in shanks 73 of members 74. It should be understood that one of the members 74 is provided at each side of the machine. A nut 75 controls the vertical position of the bolt 72 relative to the shank 73. Extending through vertically elongated apertures in each of the members 74 is a shaft 76 having a cam 77 keyed thereto within each of the members 74. Shaft 76 is journaled in member 78 fixed with respect to housings 65 and 66 and it should be apparent that upon rotation of the shaft 76 by the hand wheel 80 that the members 74 and, consequently, the blocks 69 will be raised in unison thereby separating the rolls and squeegees. Coil springs 81 apply resilient pressure between the brush rolls and the squeegees and since the upper brush rolls and squeegees are independently mounted in the blocks 69, the latter may be adjusted from time to time to compensate for wear and when the blocks 69 are raised or lowered, such adjustment is not disturbed. Brush rolls 67 and 68 are driven by motor m4 through speed reducer 82 and flexible coupling 83.

Attached to and extending forwardly of the housing 65 and 66 are the housings 85 and 86 which support at their outer ends upper and lower horizontal guide rolls 87 and vertically disposed guide rolls 88. The latter are journaled on blocks 89 positioned at either side of the machine on support 90 and, in accordance with usual practice, the blocks 89 may be moved toward and away from each other by rotation of adjusting screw 91 by the hand wheel 92. The latter adjustment is provided to accommodate strip of varied widths. An important part of the apparatus of the invention is the strip measuring device which is provided to control the operation of the apparatus in such a manner that strip pieces of predetermined length are intermittently but automatically supplied to the metal working press in synchronism with and in accordance with the demands of the press. This device consists of a pair of gauging rolls 94 arranged to be driven without slippage by the strip passing through the machine and connected through a mechanical reducer to a dial 95 adapted to be spring biased in one direction against a positive but adjustable stop 96. Note Figure 6. A magnetic clutch MC2 is interposed in the dial drive and when de-energized, the dial rotates against the stop 96. Upon being driven by measuring rolls 94, dial 95 will rotate in such direction that the stop engaging element 97 moves away from stop 96 and into sequential engagement with the operators of switches SD and MRS. The function and operations of these various parts will be explained below.

Measuring rolls 94 are journaled in frames 100 attached to the rear end of the housings 41 and 42 and to the rear of the measuring rolls 94 is a pair of pinch rolls 101 arranged to be driven from gear assembly 60 through spindle 102.

Referring now to Figure 7, the variable speed hydraulic motor hm3 which drives the cradle and pinch rolls of the uncoiler is supplied with fluid pressure from pump hp3 through conduit 104, valve 105 and conduit 106. Valve 105 is arranged to be actuated by a solenoid US and operates in such manner that when the solenoid is energized,

conduit 106 is connected with conduit 104 and when de-energized, conduit 104 is connected with a return conduit 107 leading back to a fluid storage sump 108 housed in the base of the uncoiler. Return conduit 109 is provided for the motor hm3 and the speed of rotation of the output shaft of this motor may be varied by manipulation of the hand wheel 110. Referring to Figure 9, motor m3 is energized from a suitable current source S1 through relay 3M, the coil of which is in series with control current supply line L3, conductor 112, contact UV' which is closed when the machine is set up for operation, a normally open starting switch, conductor 113, conductor 114, and control current supply line L4. In parallel with the starting switch is a normally closed stop switch in series with the holding contact 3M1 which is adapted to be closed upon energization of solenoid 3M to provide a holding circuit for the latter upon release of the starting switch button, as is well understood in the art. Solenoid US controls the operation of valve 105 and is in series with the limit switch LS1 positioned in the bottom of the loop pit 34, 35 through conductors 116, 117 and 118 and the operation of the circuit is such that the normally closed switch LS1 maintains solenoid US energized to continue the uncoiling rotation of the cradle and pinch rolls of the uncoiler until the strip reaches the bottom of the loop pit and engages the operator for switch LS1 thereby de-energizing the solenoid and stopping rotation of the coil. The electric motor and connected pump remain in operation to maintain a constant supply of fluid pressure for actuation of the fluid driving motor immediately upon the raising of the strip loop.

Energization of motors m1 and m2, which are of the reversing type, is adapted to be accomplished by suitable manually controllable circuits, not shown, and upon energization of these motors, the rotary side guides 14 are adapted to be moved inwardly or outwardly, as the case may be, to accommodate coils of strip of different widths.

In Figure 8, which is a schematic representation of the drive employed for gear case 60 which in turn operates the pinch rolls and leveller rolls of the processing leveller, as explained above, reference numeral 120 designates a four-way valve which is adapted to be operated in one direction by the solenoid C and in the other direction by solenoid B. The internal construction of valve 120 is such that when both solenoids are de-energized, the valve core automatically moves to neutral position thereby interconnecting pump output conduit 121 with pump return conduit 122 to provide an unobstructed circuit for the circulation of fluid by pump hp6 which is normally in continuous operation. Pump hp6 is of the variable displacement type, the displacement being varied by actuation of a servo-motor SM, the operation of which is in turn controlled by a solenoid A. Fluid pressure is supplied to motor SM through conduit 123 from a supercharging pump hp5 which is continuously driven by a motor m5. The operation of the displacement shifting mechanism is such that when the solenoid A is energized, the pump delivers the maximum volume for which it is adjusted and when the solenoid is de-energized, the pump delivers a much less but constant volume.

A positive displacement piston type of fluid motor hm6 is connected with valve 126 by means of conduits 123 and 123 and is operable in either direction depending on the direction of fluid flow

through the conduits. The flow and its direction is controlled by valve 120 through energization of one or the other of the solenoids B or C. When both solenoids B and C are de-energized, the ports in valve 120 communicating with the conduits 123 and 124 are closed and to provide for the drift of the rotating parts of motor $hm6$ and its connected gears, shafts and rolls as well as to accurately control the extent of such drift a bypassing conduit 125 interconnects the conduits 123 and 124 and imposed in conduit 125 is a reversible brake valve assembling 126 provided with an adjustable impeding valve 127 on conduit 123 side of assembly 126 and with a second adjustable impeding valve 128 adjacent to conduit 124. Valves 127 and 128 are operable to impede or restrict the flow of fluid through the conduit 125 to thereby control the extent of drift of motor $hm6$, while providing safety means preventing damage to any of the parts by reason of the inertia of the rotating elements. Fluid is supplied to the system from a supply sump 130 conveniently located in the base of the processing leveller by means of the continuously operating super-charging pump $hp5$ which is provided with an outlet conduit 131 connected to a central passage in view 126 and operates to expel any air which may be entrapped in conduits 123, 124, 125, valves 120 and 126, and motor $hm6$ and to maintain all the passages in these parts filled with fluid pressure. Likewise, another conduit 132 maintains pump $hp6$ and its connected conduits and passages free of air and filled with fluid. Pump $hp5$ is of the bypassing type and is provided with a return conduit 133 to return the fluid to the sump upon the attainment of predetermined pressures in the conduits 123, 131 and 132. Leakage return lines 134 and 135 are provided for pump $hp6$ and motor $hm6$, respectively.

Supported by the guide roll frame 85, 86 is a limit switch LS2 having an outwardly and downwardly extending operating arm 137 adapted to be engaged when the strip between the uncoiler and the processing leveller becomes taut and has as its principal function the stopping of the processing and feeding assembly if for any reason the uncoiler fails to deliver a proper supply of strip. Referring to Figure 9, the switch LS2, which is closed when arm 137 is not engaged, is in series across the control circuit supply line with conductor 138, a stop switch, a reset switch, an emergency stop switch, and the coil of relay UV. In parallel with the reset switch in this circuit is a holding contact UV1 and it should be apparent that upon a momentary closing of the reset switch, the coil UV will lock in and maintain closed the contact UV1, mentioned above, since the stop switches and switch LS2 are normally closed. Motor $m4$ which drives the brushing rolls of the strip scrubber is supplied with energy from source S2 through relay 4M, the coil of which is in series with the control current line through conductors 139, 140, holding contact 4M1, stop switch, switch UV1 and conductor 141. Switch UV1 is closed upon energization of coil UV, as explained above. Parallel with the last mentioned stop switch and holding contact 4M1 is a starting switch and it should be apparent that upon the momentary closing of the starting switch, the motor $m4$ will be energized and remain in operation until interrupted either by manual operation

of the stop switch or by automatic operation of the safety limit switch LS2.

Motor $m5$ which normally continuously operates supercharging pump $hp5$ for the purposes outlined above is energized from a suitable current source S3 through relay 5M, the coil of which is in series with the control current line L1, L3 through conductors 142, 143, holding contact 5M1, stop switch, switch UV1 and conductor 141. In parallel with the stop switch and holding contact 5M1 is a starting switch and it should be apparent that upon a momentary closing of the starting switch, motor $m5$ will be energized and remain in operation. In parallel with the coil of relay 5M is the coil of a second relay TR, the operated contact TR1 of which is in series with the coil of the relay controlling the supply of current to the main drive motor $m6$ to prevent operation of the latter until the supercharging pump is in operation. Motor $m6$ is supplied from a suitable current source S4 under the control of the last mentioned relay (6M), the coil of which is in series with L1, L3 through conductor 144, contacts TR1, holding contact 6M1, stop switch, switch UV1 and conductor 141. In parallel with the stop switch and the holding contact is starting switch and it should be apparent that if motor $m5$ is in operation, the momentary closing of the starting switch will lock in relay 6M thereby operating motor $m6$.

To operate the strip processing and feeding assembly in forward direction and at high or normal speed, solenoids A and B are energized with solenoid C remaining de-energized. This is accomplished by momentarily closing the "run" switch which is in series with conductors L1, L3 through switch UV2 which is closed upon energization of coil UV, limit switch MRS, conductor 145, conductor 146 and relay coil 4CR. In parallel with the "run" switch are the holding contacts 4CR1 and upon energization of coil 4CR, contacts 4CR2 in conductor 147 are closed which results in energization of relay coil 6CR which is in series with contacts 4CR2. Simultaneously, contacts 4CR3 in conductor 148 are closed and this results in energization of relay coil 1CR which is in series with contacts 4CR3, it being apparent that coils 1CR and 6CR derive their energy from conductors L1, L3 through switch UV2. Upon energization of coils 1CR and 6CR, contacts 1CR1 in conductor 150 are closed as are also the contacts 6CR1 in conductor 151. The closing of the former energizes solenoid A and the closing of the latter energizes solenoid B. Assuming that the machine is operating at its normal or high speed by reason of the energization of solenoids A and B, and that strip is being fed therethrough, such operation will continue until the first limit switch SD (normally closed) on the measuring device is opened by reason of a predetermined progression of the strip at which time the coil 1CR will be de-energized. By referring to the bottom of Figure 9, it can be seen that the switch SD is in series with the coil 1CR. When the latter is de-energized, contacts 1CR1 are opened and circuit 150 broken thereby de-energizing solenoid A. This action reduces the displacement of the pump $hp6$ in the manner explained above and, therefore, reduces the speed of rotation of the output shaft of motor $hm6$ which is connected to the pump by solenoid B acting through valve 120. The machine then continues to operate at this substantially reduced speed until the second limit switch MRS, normally closed,

of the measuring device (Figure 6) is opened which action interrupts circuit 146 and de-energizes coil 4CR. At this time contacts 4CR2 in conductor 147 are opened and coil 6CR is accordingly de-energized. De-energization of 6CR opens contacts 6CR1 in conductor 151 thereby de-energizing solenoid B and allowing the valve 120 to shift to neutral position. Conduits 121 and 122 are now interconnected to provide a free circulating passage for the fluid handled by pump hp6 and at the same time the conduits 123 and 124 are closed off at the valve 120. Valve assembly 126 now acts as a brake causing the discharge from the motor hm6 to pass over the relief valves 127 and 128 within the assembly, the pressure setting of the relief valves determining the braking effect. This action provides a means of absorbing the inertia energy of the moving strip and rotating parts of the machine to bring the same to a quick but controlled stop. It is possible to accurately gauge the extent of overrun and by setting the switch MRS accordingly, a highly accurate control over the quantity or length of the strip fed may be exercised. To facilitate the setting up of the machine and the threading through of the stock, relays 1CR and 6CR are provided with inching switches, the operation of which should be readily apparent from Figure 9 of the drawings.

The machine may be reversed under manual control by depressing the reversing switch in line 152 to energize the coil of relay 7CR. Contacts 7CR1 are closed upon energization of coil 7CR and are in series with solenoid C across the line L1, L3 and when solenoid C is energized, valve 120 is actuated so as to divert the output from pump hp6 to the opposite side of motor hm6 to cause the latter to rotate in the reverse direction. Referring to Figure 9, near the top thereof, it will be observed that contacts 7CR2 are in series across the line L1, L3 with the coil of the magnetic clutch MC1. As explained above, the clutch MC1 is provided for the purpose of bridging the free wheeling drive for pinch rolls 50 so that these rolls may be driven in the reverse direction in backing up the machine.

To arrange the strip processing and feeding assembly for operation in synchronism with an automatic stamping press and the like, a switch P1 is positioned on the press or other machine in such manner that it is momentarily closed if the previously worked piece has been removed from the press or machine and the latter is in condition to receive and work on a new piece of strip. Switch P1 is located in line 153 which is in parallel with the "run" switch. In series with switch P1 is a switch AM which is manually closed when the machine is set up for automatic operation. To operate the magnetic clutch MC2, an operating solenoid therefor is in series with the line L1, L3 and switch contacts 5RC1, the latter of which are adapted to be closed by energization of relay 5CR which is in series with L3, UV2, conductor 154, normally closed switch P2, a manual clutch reset switch and normally closed switch 7CR3. This is shown in Figures 6 and 9. Switch P2 is also mounted on the press (shown at 165 in Figure 6 as a representation of any conventional press) and is adapted to be momentarily opened as the press opens up immediately upon completion of a working operation. The momentary opening of switch P2 momentarily de-energizes the magnetic clutch MC2 thereby allowing the spring 155 to move the dial 95 of the measuring device (Figure 6) back to its original start.

ing position in preparation for a new measuring cycle.

In general, therefore, the operation of the machine is such that the switch SD of the measuring device slows the machine down and the switch MRS thereof stops the operation of the machine with the strip advanced to its exact proper position in the press. Automatic means, not a part of the invention and therefore not shown, now operates the press and immediately thereafter the switch P2 is opened to move the dial 95 to its original position and close switches SD and MRS. It should be remembered that the opening of MRS de-energized coil 4CR and took out its holding circuit which is in parallel with the manually engageable "run" switch. Consequently, upon the re-closing of MRS, coil 4CR is not re-energized nor is the machine again started until the switch P1 is closed in the manner aforesaid. Upon the momentary closing of switch P1, coil 4CR is energized and held in by its holding contacts 4CR1.

In addition to the automatic controls outlined above, means is provided to automatically raise and lower the working roll 43 of the strip processing assembly which roll is operated by motor RM. As explained above, roll 43 is raised and lowered by a crank and it should be apparent that rotation of the crank in one direction through 180° may move the roll from top to bottom position and continued rotation through another 180° may move the roll back to top position. Therefore, motor RM may be uni-directional. This motor is provided with a magnetic brake MB1 to insure its stoppage at the proper positions and is energized from a suitable source S5 under the control of relay 8CR. The coil of relay 8CR is in series with line L1, L3, conductor 160, a normally closed limit switch UL1 which is opened when the working roll 43 reaches its upper position, and normally opened switch contacts 2CR1. Coil 2CR which operates contacts 2CR1 is in series with L3, switch HR which is a thermal guard on motor RM, normally closed switch AM1, conductor 161, a strip detecting switch 162, a conductor 163 and L1. Switch 162 is incorporated in the processing machine in such manner that as the leading end of the strip is engaged by both pairs of pinch rolls 51, the switch will be closed thereby energizing coil 2CR and operating motor RM. If the working roll 43 is in its lower position rotation of RM continues until limit switch UL is opened indicating that the roll 43 has reached its upper position. It should be observed that additional contacts 2CR2 are provided on relay 2CR which additional contacts are closed when coil 2CR is energized and which are in series with the coil of relay 3CR and therefore upon de-energization of relay 2CR, relay 3CR is energized. Contacts 3C1 which are closed by energization of relay 3CR are in series with a limit switch DL representing the lower position of working roll 43, conductor 160 and relay 8CR. It should, therefore, be apparent that when there is no strip in the machine as detected by switch 162, the roll 43 is automatically moved to lower position. Signal light L in series with limit switch DL is provided to warn the operator that the working roll 43 is not in its lowermost position, as some damage may result if the strip is fed into the machine while the working roll 43 is not in its lowermost position. Switch AM1 is closed for automatic operation and manually opened for manual control of the motor RM. Motor RM may be then manually controlled by

manipulation of the push buttons shown whose operation should be apparent upon an inspection of Figure 9 of the drawings.

It should now be apparent that I have provided an improved method and apparatus which accomplishes the objects initially set out. By employing the principles of the invention, it is possible to feed metal strip from the coils thereof directly to a metal working press and the like and simultaneously with the feeding to process and condition the strip as well as to accurately measure and control the amount of strip handled. This objective is accomplished by means of compact and rugged apparatus which lends itself readily to automatic control synchronized with the cyclic operation of the machine to which the strip is supplied and, in practice, these advantages total up to substantial savings in stock loss, machine time and labor costs. Moreover, by reason of the fact that the strip passes directly from a de-scaling and cleaning station to a processing and leveling station and thence directly to the machine utilizing the strip, the strip arrives at the working station in the latter machine in substantially improved condition thereby increasing the quality of the product of the latter machine. Another important practical advantage to the apparatus of the invention is the fact that the above advantages may be attained by means of apparatus which does not require a great amount of factory floor space for its installation and operation. Moreover, the control of the entire apparatus is such that it may be remotely accomplished and thus its control station may be combined with the control station of the metal working press or other apparatus to which the treated strip is fed thereby further facilitating the operation of the plant.

The above specifically described embodiment of the invention should be considered as illustrative only as obviously many changes may be made therein without departing from the spirit or scope of the invention. For example, while the particular measuring device employed in the machine is provided with means to first slow down the speed of the apparatus and to thereafter stop the apparatus, it should be apparent that other means may be employed to stop the apparatus after a pre-determined amount of the strip has been fed. It is specifically contemplated that such alternate means may comprise a controlled and synchronous decelerator which is operative to insure the stoppage of the rolls at exactly a predetermined linear interval after a position response is made and by allowing for this interval in setting the position of the response device, a highly accurate control of the length of strip fed may be accomplished. Reference should therefore be had to the appended claims in determining the scope of the invention.

What I claim is:

1. In apparatus for conditioning and feeding metal strip to a metal working press and the like the combination of a strip uncoiler having means to support and rotate a coil of strip, a processing unit positioned immediately behind said uncoiler for receiving strip therefrom and having a working roll adapted to be moved through the plane of the strip pass through the apparatus to subject the strip to severe reverse bendings as it passes through the apparatus, a roller leveller, a strip measuring device, means responsive to the operation of said measuring device to interrupt the operation of said leveller and processing unit upon passage therethrough

of a predetermined length of strip, a loop pit adapted to receive a supply of the strip positioned intermediate the said uncoiler and said processing unit, and means responsive to the size of the strip loop in said pit to interrupt said first mentioned rotating means.

2. Apparatus according to claim 1 further including control means adapted to be actuated following the completion of the feeding of a predetermined length of strip, and means operative upon actuation of said control means to prepare said measuring device for a new measuring cycle and in turn to restore the operation of said processing unit and leveller.

3. In apparatus for conditioning and feeding metal strip to a metal working press and the like the combination of a processing unit including a metal working roll adapted to be moved through the plane of the strip pass through the apparatus to subject the strip to severe reverse bends as it passes through the apparatus and a roller leveller, means to drive said processing unit, a strip measuring device positioned at the strip leaving end of said unit, and means controlled by said measuring device to interrupt the operation of said driving means for said processing unit.

4. Apparatus according to claim 3 further characterized in that said unit includes a pair of pinch rolls intermediate said metal working roll and said roller leveller, said driving means being operative to drive said pinch rolls and the rolls of said roller leveller, said driving means being operative to drive all of said rolls at changed speeds, and further means responsive to the operation of said measuring device to change the speed of rotation of all of said rolls.

5. In apparatus for conditioning and feeding metal strip to a metal working press and the like the combination of a strip processing unit including a metal working roll adapted to be moved through the plane of the strip pass through said unit whereby said strip is subjected to severe reverse bends as the strip passes therethrough and a roller leveller, said unit including a pair of pinch rolls intermediate said metal working rolls and the rolls of the leveller, means to drive all of said rolls in unison, means to change the speed of rotation of said rolls, a strip measuring device positioned adjacent the leaving end of said unit, and means responsive to operation of said measuring device to first decrease the speed of rotation of said rolls and to thereafter render inoperative said rotating means.

6. Apparatus according to claim 5 further including means to control and adjust the drift of said rolls after said rotating means has been rendered inoperative.

7. In apparatus for conditioning and feeding metal strip to a metal working press and the like the combination of a processing unit including a metal working roll adapted to be moved through the plane of the strip pass through said unit whereby the strip is subjected to severe reverse bends as it passes through said unit and a roller leveller, a pair of pinch rolls intermediate said metal working roll and the rolls of the leveller to draw said strip about said metal working roll, means to rotate all of said rolls in unison comprising a fluid pressure motor, a variable delivery fluid pump, means to drive said pump, means to vary the output of said pump, means to measure the strip as it issues from said unit, means responsive to operation of said measuring device to actuate said means to vary the output of said pump, and means responsive to further operation

of said measuring device to disconnect the output of said pump from said motor.

8. Apparatus according to claim 7 further including means to control and adjust the drift of said rolls upon actuation of said disconnecting means.

9. Apparatus according to claim 7 further including a closed path through which the fluid contained in said motor upon actuation of said disconnecting means may circulate, and means to vary the resistance of flow of the last mentioned fluid through said closed passage.

10. In apparatus for conditioning and feeding metal strip to a metal working press and the like the combination of a strip uncoiler having means to support and rotate a coil of strip, a processing unit having a working roll adapted to be moved through the plane of the strip pass through the apparatus to subject the strip to severe reverse bendings as it passes through the apparatus and a roller leveller, a loop pit adapted to receive a supply of strip positioned intermediate said uncoiler and said processing unit, and means responsive to the position of the strip loop in said pit to interrupt the operation of said first mentioned rotating means when a predetermined supply of strip is deposited in said pit.

11. Apparatus according to claim 10 further including a pinch roll intermediate said working roll and said roller leveller to draw the strip over said working roll, means to rotate said pinch rolls and the rolls of said roller leveller in unison, and means responsive to a second position of the strip in said pit to interrupt the last mentioned rotating means when the supply of strip in said pit is deficient.

12. In apparatus for feeding metal strip to a metal working press and the like a strip uncoiler comprising in combination a pair of cradle rolls adapted to support and rotate a coil of strip, a pair of pinch rolls positioned above and to one side of said cradle rolls and arranged to rotate about spaced parallel axes parallel with the axes of rotation of said cradle rolls, the pass plane of said pinch rolls being adjacent the outer periphery of a coil supported on said cradle rolls and being substantially tangent to the strip emanating therefrom along a short spiral curve extending downwardly and outwardly from a line positioned centrally above and parallel with the axes of said cradle rolls, and means to drive said cradle rolls and said pinch rolls in unison.

13. Apparatus according to claim 12 further including a downwardly looped roller table positioned below and to one side of said pinch rolls to receive the strip issuing from said pinch rolls whereby the strip is caused to follow an S-curved path as it comes off a coil support on said cradle rolls.

14. In apparatus for uncoiling and feeding metal strip to a metal working press and the like which requires a predetermined length of strip in each cycle of operation the combination of an uncoiler having means to support and rotate a coil of strip, means comprising a switch responsive to the position of a loop in the uncoiled strip adjacent the uncoiler to interrupt said rotating means upon said loop attaining a predetermined size, a pair of pinch rolls to receive the strip from said loop and move the same into said press and the like, means responsive to the length of strip passing through said pinch rolls to inter-

rupt operation of said rolls upon said predetermined length of strip being fed, and means responsive to a shortened condition of said loop to stop rotation of said pinch rolls when the length of strip in said loop reaches a minimum value.

15. In apparatus for conditioning and feeding metal strip to a metal working press and the like the combination of a strip uncoiler having means to support and rotate a coil of strip, a strip processing and levelling unit having means to drive the rolls thereof, a loop space between said uncoiler and said unit, means including a switch in said space adapted to be actuated by the attainment of a strip loop of predetermined proportions to interrupt operation of said coil rotating means, and means including a second switch in said space operable upon a predetermined decrease in said loop to interrupt the operation of said coil rotating means and of the means to rotate the rolls of said unit.

16. In apparatus for conditioning and feeding metal strip to a metal working press and the like the combination of a base, a pair of spaced parallel housings mounted on said base, pairs of pinch rolls journaled in said housings to guide the strip horizontally through the apparatus, a working roll adapted to be moved through the plane of the strip pass whereby the strip is subjected to severe reverse bends as it passes through said apparatus, a roller leveller having its rolls journaled in said housings and being operative to level the strip after it passes over said working roll, one of said pairs of pinch rolls being positioned intermediate said working roll and said leveller, means to rotate the rolls of the said one of said pairs of pinch rolls and the rolls of said leveller, a strip measuring roll journaled in said housings, and means operable in response to a predetermined rotation of said measuring roll to interrupt said roll rotating means.

17. In apparatus for conditioning and feeding metal strip from coils of such strip directly to a metal working press and the like which requires a predetermined length of strip in each cycle of operation the combination of a strip uncoiler having means to support and rotate a coil of strip and further means responsive to the position of a looped portion of the strip as it leaves said coil in control of said rotating means, a processing and feeding unit positioned immediately beyond said means and having a working roll adapted to be moved through the plane of the strip pass to subject the strip to severe reverse bendings and a roller leveller, a strip measuring device immediately beyond said leveller and adapted to control the rotation of the rolls of said roller leveller, said measuring device having a member movable in proportion to the movement of strip and means adapted to be actuated upon a predetermined movement of said member, said last mentioned means being effective to stop rotation of the rolls of said roller leveller, control means adapted to be actuated following the completion of the feeding of a predetermined length of strip, and means operative upon actuation of said control means to return said member to its initial starting position thereby preparing said measuring device for a new measuring cycle, and means operative substantially simultaneous with the said return of said member to reinitiate rotation of said rolls.

RUSSELL T. TODD.
